UNITED STATES PATENT OFFICE.

HANS RASMUSSEN, OF CHICAGO, ILLINOIS.

SECURING DEVICE FOR CONCRETE-FORMS.

1,192,115.

Specification of Letters Patent. Patented July 25, 1916.

Application filed January 31, 1916. Serial No. 75,384.

To all whom it may concern:

Be it known that I, HANS RASMUSSEN, a citizen of the United States, residing at Chicago, in the county of Cook and State of Illinois, have invented certain new and useful Improvements in Securing Devices for Concrete Forms, of which the following is a description, reference being had to the accompanying drawings, forming a part of this specification, in which corresponding numerals of reference in the different figures indicate like parts.

The object of my invention is to provide a simple, cheap and effective device for holding concrete forms in place while being filled with concrete in the erection of walls, pillars, and other analogous structures,—the aim being to construct said device that the main tie members may be permitted to remain within the wall after the removal of the forms and that without any projecting portion to cause defacement of the wall or to require removal after the form is taken away.

A further object is to so construct said device as to obviate the necessity for skilled labor in connection with its use.

To these ends, my invention consists in the combination of elements hereafter more particularly described and definitely pointed out in the claims.

In the drawings, Figure 1, is a plan of a form such as is ordinarily employed in the construction of a concrete wall showing my improved fastening devices as they would be used in connection therewith, Fig. 2, is a vertical section taken upon the line 2—, Fig. 1, viewed in the direction of the arrow there shown, Fig. 3, is a perspective view in detail of two anchoring members, as they would appear when viewed from opposite ends and Fig. 4, is a transverse vertical section of a portion of a concrete wall with an anchoring member therein as it would appear after the removal of the form.

Referring to the drawings, 1, 1, indicates the walls of the form, ordinarily consisting of boards arranged horizontally upon edge, 2, the vertical ribs usually made of two-by-four scantling and 3 the horizontal braces. The walls 1, are spaced and held apart by means of struts or separating bars 4. The bracing timbers 3 and walls 1 are provided with bores in proper registration for the reception of lag-screws 5 of sufficient length to pass through said parts and a short dis-

tance into the space to be occupied by the concrete wall. Anchor-nuts, generally designated by 6, comprising elongated members, preferably formed from cast-metal, are provided with longitudinal screw-threaded bores 7, Fig. 3, for the reception of the lag-screws 5. Each anchor-nut is provided upon its periphery with a projection 8, extending about half way around said nut and preferably from about the middle to a point at or near the inner end. Said projection is provided with a transverse shouldered portion 9 and longitudinal shouldered portions 10, the latter being in a plane parallel to the axis of the nut. Both shouldered portions are, by preference, grooved as best shown in Fig. 4, to receive and form an anchorage for the loop 11, of a tie-wire generally designated by 12. The tie-wire is cut to a predetermined length so that when secured in place the anchor-nuts will be properly spaced with reference to a given width of wall, allowance being made for the twisting of the wires. Said wire is then looped so as to partially surround each nut and rest against the shoulder 9 as shown at 11, after which it is bent longitudinally of the nut so as to bear against the shoulders 10 upon opposite sides of the nut and in the plane of its axis. The end portions of the wire are then overlapped and securely twisted around the body portion as shown at 13. After looping the wire upon the anchor-nut and fastening the ends together, the loops will 90 clasp the nuts with sufficient closeness to remain in permanent connection so as to enable them to be handled and treated as one piece. They are then ready for use in the wall.

The invention may be utilized as follows: The holes for the screws 5, are bored in proper alinement in the walls and the anchor-nuts, connected as described, are held by an attendant opposite the bores. The lag screws 5, with washers 14 thereon, are then projected through the bores into the anchor-nuts and tightened so that the wall members 1, of the form, will press against and hold the struts 4 in place. The length of the tie-wires should be such that when thus tightened, the outer ends of the anchor-nuts shall be about half an inch, more or less, from the respective inner faces of the retaining walls. The concrete is then filled in and allowed to set, care being taken to remove the struts 4, as the work is advanced. When ready to

remove the forms, an attendant takes out the lag-screws, leaving the anchor-nuts and tie-wires in the wall. A slight cavity, as shown at 15, Fig. 4, is left in the face of the wall 5 opposite each anchor-nut, which space may be readily filled with cement thereby presenting a smooth and perfect surface.

By using a tapered or pointed lag-screw, as shown at 16, Fig. 2, the screws may be 10 made to engage the nuts with ease and rapidity. By constructing the nuts with the shouldered portions described, the pull of the connecting wires will always be in the plane of the axis of the nut, while the 15 method of attachment is rendered simple and easy.

My improved tie may be manufactured ready for use with a view of leaving it permanently in the wall, thereby eliminating 20 the cost of cutting wire ties and the disfigurement of the walls resulting from the projecting wire ends and the rust-stains caused thereby. Moreover, no skilled labor need be required either in the placing of the 25 ties or the removal of the forms. The lag-screws may be kept as a permanent part of the contractor's equipment to be used over and over again.

Having thus described my invention, I 30 claim:

1. A fastening device for securing the walls of concrete forms in spaced relation to each other, comprising, in combination, complementary anchoring members adapted to be located within the wall-space away from but near to the respective side-walls of a form, said members having interior screw-threads for receiving lag-screws adapted to be extended inwardly thereto through said 35 walls, each of said anchoring members being provided with peripheral wire engaging means to enable a wire to be looped over the body thereof and extended and secured between them in the plane of their axes and a looped wire tie for engaging said engaging 40

means to form a connection between said anchoring members.

2. A fastening device for securing the walls of concrete forms in spaced relation to each other, comprising, in combination, complementary anchoring members adapted to be located within the wall-space away from but near to the respective side walls of a form, said members having interior screw-threads for receiving lag-screws adapted to 50 be extended inwardly thereto through said walls, each of said anchoring members being provided with peripheral wire engaging means to enable a wire to be looped over the body thereof and extended and secured between them in the plane of their axes, a looped wire tie for engaging said peripheral 55 engaging means to form a connection between said anchoring members and lag-screws for securing said anchoring members 60 to the walls of said form.

3. A fastening device of the class described, comprising, in combination, elongated complementary anchoring members adapted to be located in the wall-space at a 70 predetermined distance from the respective side-walls of a form, said members having interior screw-threaded bores for receiving lag-screws adapted to be extended inwardly from opposite directions through said walls 75 in alignment with said anchoring members, each of said anchoring members having a peripheral shoulder extending outwardly from its body, and partially surrounding said member, for receiving a wire loop thereover to form a connecting tie between said members and holding said wire in the axial 80 plane of the latter.

In testimony whereof, I have signed this specification in the presence of two subscribing 85 witnesses, this 29th day of January 1916.

HANS RASMUSSEN.
